57,815.

Specification for Design. Patented May 10, 1921.

Application filed September 26, 1919. Serial No. 326,685. Term of patent 14 years.

To all whom it may concern:

Be it known that I, JOHN C. BROWN, a citizen of the United States, residing at Minneapolis, in the county of Hennepin and State of Minnesota, have invented a new, original, and ornamental Design for a Pastry-Tool, of which the following is a specification, reference being had to the accompanying drawing, forming part thereof.

Figure 1 is a plan view of the pastry tool, showing my new design.

Fig. 2 is a side elevation of the same.

I claim:

The new and ornamental design for a pastry tool, as shown.

JOHN CLARK BROWN.
